UNITED STATES PATENT OFFICE.

THADDEUS STEPHENS CASNER, OF PLAINFIELD, NEW JERSEY, ASSIGNOR TO RADIO ELECTRIC CLOCK CORPORATION, OF NEW YORK, N. Y., A CORPORATION OF DELAWARE.

SILENT SECONDARY CLOCK.

Application filed May 29, 1926. Serial No. 112,542.

This invention relates to intermittently operating electrical devices and particularly to electro-magnetically operated clocks.

The principal object of this invention is 5 to provide an improved drive mechanism for intermittently operating devices such as electrical secondary clocks, which are in circuit with a control device for instance a master clock, which makes and breaks a 10 circuit through a source of electrical energy.

An objectionable feature of devices of this character heretofore created or suggested is that a mechanical, usually metallic, sound is made whenever the electrical driving mechanism is operated. This sound is in some 15 cases caused by an armature oscillating between fixed stops, in other cases by the movement of pawls over ratchets, and by various other operating parts. It is obvious that 20 where quiet is desired, as for instance in hotel rooms, in schools, in theatres, and in private homes, these noises, however faint, because of their metallic character and ceaseless regularity are irritating to persons situated near the instrument.

The present invention therefore has for a further object the provision of electro-magnetic drive mechanism which shall be noiseless in its operation, and which shall 30 have no parts the operation of which may result in audible sounds.

A further object of the invention is the provision of an apparatus of this class having few parts and these of a simple character, which is readily accessible for cleaning and oiling, and which is of small size, rendering it convenient for use with wall 35 clocks, desk clocks, punch clocks, automatic temperature recording mechanisms, seismographs, and many other devices.

The invention will be described as applied to secondary electric clocks though it will be evident that it is adapted to be used with various other devices. One form of the 45 invention is described herein and illustrated in the accompanying drawings, in which:

Fig. 1 is a front elevation of a secondary clock embodying this invention, the gearing to the clock hand shafts other than the 50 minute shaft being omitted for the sake of clearness;

Fig. 2 is a side elevation of the device shown in Figure 1; and

Fig. 3 is an enlarged view of a detail shown in Figure 1, parts being shown in 55 a different position.

A pair of electro-magnets M, M are connected together by a fixed yoke A which for convenience is bent downwardly along the sides of the magnets to form bearings for 60 the shafts of the mechanism operated by the magnets, as will be described below. The poles P, P of the magnets are formed with concavities 11, 11 along their sides or at their ends to allow a moving armature 12 65 to rotate therebetween. This armature is made approximately Z-shaped with the exception of the wings 13 of the armature, which are given a curved outline to move with a variable clearance between the 70 concavities of the pole pieces. The wings of the armature are made of varying cross sectional area from the tip to the heel, having the greatest area near the heel. This construction provides the proper rotatable pull upon 75 the armature when the magnet is energized. A shaft 14 rotatably supports the armature 12 between the pole pieces, the bent portions 15 of the yoke A having bearings 16 formed therein for this purpose.

Another shaft 18 is also rotatably carried in bearings 19 in the extensions 15. The shaft 18 constitutes the minute shaft of the secondary clock when the mechanism is used for operating a secondary clock. This is 80 provided for by securing thereon a toothed wheel 20 which has sixty teeth so that it makes one revolution every hour when geared to mechanism designed to move it through the distance of one tooth space per 85 minute. The shaft 18 also carries a pinion 21 designed to connect it to the hour hand of the secondary clock through the usual gearing. The illustration of this gearing is omitted from the drawings for the sake of 90 clearness.

The shaft 14 carries, in addition to the armature 12, a disk 25, rigidly secured thereto. The disk 25 is thus rotatable with the armature and operates the toothed wheel 100 20 of the minute shaft through two pins 26, 26 secured to one side of the disk on opposite sides of, and in axial alignment with, the shaft. The purpose of having two pins instead of a greater number is to 105 provide a one-way drive for the clock hands,

With this drive arrangement the clock gear train cannot be moved except by the armature and pins and hence the hands cannot be accidentally moved to give the clock a wrong setting. It is also to be noted that the pins 26 are disposed in a line oblique to the axis of the connecting bar of the armature 12, 13. This arrangement provides for having both pins between teeth of the toothed wheel when the armature is in its unattracted or rest position, and also causes the rear pin to engage a tooth immediately the tips of the armature wings begin to be attracted by the magnet. By having the pins strike the teeth while the armature is moving slowly from rest all metallic blows and noises between these parts are avoided.

On the opposite side the disk carries a second pair of pins 30 spaced approximately 90° from the first pair of pins. The pins 30 operate against a spring 35 having its axis generally parallel to a line joining shafts 14 and 18. In its preferred form the spring is of the hair pin type, as illustrated, to provide a balanced pressure on the sides of shaft 14, though it is evident that a single pronged spring might be used. The spring 35 is supported by a screw 36 secured in one of the yoke extensions 15. Preferably also the pins 30 carry grooved rollers 31 to provide easy movement along the prongs of the spring. In the position of rest the rollers are aligned along the axis of and between the prongs of the spring as shown in Figure 1. In this position the prongs of the spring bear but lightly on the rollers and no considerable force is required to be exerted on the armature to move the rollers against the spring pressure.

The operation of the mechanism will be apparent. Closure of a switch by a master clock at minute intervals causes the armature to be moved from the position of rest, shown in Figure 1 to the position shown in Figure 3 wherein the bar of the Z-shaped magnet is aligned between the magnet poles. In this movement of the armature, which is greater than 90° the rollers between the springs are moved from the aligned position to a position just beyond dead center with respect to the springs. Then when the master clock breaks circuit to deenergize magnets, the spring 35 by pressing on the rollers causes the shaft to complete a movement of 180° from the initial position and thereby move the toothed wheel by pins 26 through a distance of one tooth space. The spring 35 is made just strong enough to cause the rollers to move when the magnet is deenergized but not strong enough to rotate the rollers and shaft with sufficient force to cause a blow when the rollers contact the opposite prongs of the spring at the end of the movement.

Having thus described the invention what

is claimed as new and desired to be secured by Letters Patent is:

1. Mechanism for intermittently rotating a shaft or other rotatable element, including, a shaft, a disk mounted on the shaft, two pins carried by the disk on opposite sides of the shaft, a toothed wheel meshing with said pins, two rollers also carried by the disk on opposite sides of the shaft and spaced approximately 90° from the pins, a spring adapted to bear against the rollers and to yieldably hold the shaft in either of two definite normal positions 180° apart, and means for initiating movement of the shaft to rotate the rollers thru an angle greater than 90° from either normal position, the spring then acting on the rollers to cause the shaft to complete a movement of 180° from initial normal position to cause said pins to move the toothed wheel through the distance of one tooth space.

2. Mechanism for intermittently rotating a shaft or other rotatable element, including, a shaft, a disk mounted on the shaft, two pins carried by the disk on opposite sides of the shaft, a toothed wheel meshing with said pins, two rollers also carried by the disk on opposite sides of the shaft and spaced approximately 90° from the pins, a spring adapted to bear against the rollers and to yieldably hold the shaft in either of two definite normal positions 180° apart, and means for initiating movement of the shaft to rotate the rollers thru an angle greater than 90° from either normal position, said means including a Z-shaped armature carried by the shaft between the poles of an electro-magnet having the axis of the connecting bar thereof oblique to the line joining said pins, the spring being operative when the armature is released by the magnet to complete a movement of 180° from the initial normal position to cause said pins to move the toothed wheel through the distance of one tooth space.

3. A magnetic secondary clock, comprising in combination, an electro-magnet having aligned and spaced poles, a Z-shaped armature supported on a shaft between the poles, a disk carried by the shaft, a pair of pins carried by the disk on opposite sides of and coaxial with the shaft, the pins being disposed at an oblique angle to the axis of the connecting bar of the armature, a toothed wheel meshing with said pins, a second pair of pins also carried by said disk and disposed at an angle of approximately 90° from the first pair of pins, a hair pin spring engaging the second pair of pins to yieldingly hold the shaft in either of two definite normal positions 180° apart, said magnet when energized causing said second pair of pins to rotate thru an angle greater than 90° from the normal position so that when the armature is released the spring will act on

the second pins to cause the shaft to complete a movement of 180° from the initial position, the first pins meanwhile operating to move said gear wheel through the distance of one tooth space.

4. Mechanism for intermittently rotating a shaft or the like including in combination, a toothed wheel mounted on the shaft, a second shaft rotatable about a fixed axis, two spaced pins carried by the second shaft and normally lying in adjacent notches of the toothed wheel, and means for intermittently rotating said second shaft thru a half rev-

olution, said toothed wheel being advanced one tooth by said pins for each half revolution of said second shaft. 15

5. A device as claimed in claim 4 in which said second shaft also carries a pair of spaced rollers thereon, and resilient means normally tending to maintain said rollers and shaft in such position that an axial plane passing thru the pins is tangential to the toothed wheel.

In testimony whereof I hereunto affix my signature.

THADDEUS STEPHENS CASNER.
